MAGNETRON OSCILLATORS

William Ernest Willshaw, Kenton, England, assignor to
The M-O Valve Company Limited, London, England

Application February 26, 1952, Serial No. 273,436

Claims priority, application Great Britain
February 28, 1951

8 Claims. (Cl. 250—36)

This invention relates to magnetron oscillator devices of the multiple resonant cavity type comprising a metal block anode formed with a cylindrical electron orbit hole within which lies a thermionic cathode and having a plurality of resonant cavities recessed into the metal block, the cavities being spaced round the cathode and opening on to the electron orbit hole.

Such magnetron devices are adapted to co-operate with magnetic fields for the generation of electrical oscillations and are especially suitable for the generation of oscillations of very high frequency. In some cases it is desirable to arrange that the frequency of the oscillations generated can be varied during operation of the oscillator, and mechanical tuning means for effecting such frequency changes are well known; means for effecting the changes electronically have also been used or proposed, such means in general comprising means for producing a stream or cloud of electrons with which the electromagnetic field of the resonant system of the magnetron oscillator can interact, the interaction resulting in a change in the operating frequency of the oscillator.

The object of the invention is to provide an improved form of magnetron oscillator device of the type specified provided with means for effecting an electronic control of the operating frequency of the oscillator.

According to the invention a multiple resonant cavity magnetron oscillator device of the type specified includes an auxiliary thermionic cathode located within one of the said resonant cavities and is provided with leads suitable for energizing and supplying operating current to the auxiliary magnetron diode formed by the co-operation of the metal block anode and said auxiliary cathode.

We have found that with the construction in accordance with the invention, when the magnetron oscillator is operated under the normal conditions with the auxiliary diode not energised, the normal operating frequency is obtained and there need be little loss of output power occasioned by the presence of the diode; but if the auxiliary diode is then energised with anode-cathode voltage difference below the cut-off value for such a diode, the operating frequency of the oscillator is decreased and the frequency shift produced can be varied by increasing or decreasing the current taken by the diode. We believe that this frequency dependence is due to the formation of an electron cloud around the auxiliary cathode of the diode, which cloud acts as a reflector to electromagnetic waves impinging on its surface and modifies the electrostatic capacity of the resonator system; variation of the diode current results in a change in the cloud size and hence in the electrostatic capacity of the resonator system, with resulting change in the frequency of operation of the oscillator.

The change in operating frequency of the magnetron oscillator is accompanied by some loss of output power, but we have found that by careful design the loss of power can be limited to relatively small values, for example less than 20%; for minimising loss of power it is de-

2

sirable for the uniformity of the magnetic field with which the magnetron oscillator device co-operates to extend not only across the electron orbit hole but also to the cavity including the auxiliary cathode, and for this reason magnetic pole-pieces of somewhat greater area than usual are desirable with the arrangement in accordance with the invention; it is also desirable that the auxiliary cathode should be accurately centred in the cavity in which it is situated and that it should be slotted to minimise the circulating current induced in it by the oscillating field within the cavity.

Usually the resonant cavities in a magnetron oscillator device of the kind to which this invention relates are formed by cylindrical slots traversing the metal block anode with their axes parallel to the axis of the electron orbit hole, and the auxiliary thermionic cathode provided in accordance with the invention is then preferably also cylindrical and arranged with its axis parallel to the axis of the electron orbit hole. Where the auxiliary cathode lies within a part of a cavity which is substantially of circular cross-section, the auxiliary cathode is preferably also of substantially circular cross-section and co-axial therewith.

The manner of operation of the auxiliary diode in a magnetron oscillator device in accordance with the invention will depend on the use to which it is to be put. Thus, for example, if a simple shift from one value to another in the operating frequency of the oscillator is required, the auxiliary cathode may be merely arranged to be connected to the anode through a switch, closing of the switch in operation of the oscillator connecting the auxiliary cathode directly to the anode, thus rendering the auxiliary magnetron diode operative and reducing the operating frequency of the oscillator; for obtaining an increased frequency drop it may be arranged that the diode current is increased by overloading the magnetron oscillator and/or by increasing the anode-cathode voltage of the diode, but this will also further decrease the output power.

It will be appreciated that the frequency changes obtained with a magnetron oscillator device in accordance with the invention are related to variations in the other parameters of the oscillator and to the operating conditions of the diode and that all such factors must be taken into account and may be taken advantage of in applying the magnetron oscillator device to any particular use.

The invention will be further described with reference to one particular embodiment, which is given by way of example and is illustrated in the accompanying drawing in which

Figure 1 shows a perspective view of the magnetron oscillator device, partly cut away to reveal the internal details,

Figure 2 shows an end view of the device, with one end plate removed,

Figure 2(a) shows a detail of the reverse side of Figure 2,

Figure 3 shows a section in the plane A—A of Figure 2, and

Figures 4, 5 and 6 show schematically different circuit arrangements for the operation of the magnetron oscillator device shown in Figures 1 to 3.

Referring now to Figures 1 to 3, the magnetron oscillator device shown comprises a cylindrical copper block 1 recessed from each end face 2 to leave a central partition 3 which forms the anode proper, this partition being perforated by a cylindrical hole 4 which forms the electron orbit hole and by eight resonant cavities (5, 6) which open into the electron orbit hole and are spaced symmetrically round its axis; each cavity is in the form of a cylindrical hole 5 having its axis parallel to the axis

of the electron orbit hole and communicating with that hole through a narrow radial slot 6.

A cylindrical indirectly heated thermionic cathode 7, provided with circular end discs 8 in the usual manner, is supported within and coaxial with the electron orbit hole by two stout conductors 9 lying one on each side of the central partition and insulatingly sealed through the curved wall of the block through glass-to-metal thimble sidearm seals 10 in the usual way. The cathode is insulated from one of the discs 8 for enabling current to be passed through the cathode heater 7' from the conductors 9, in the usual way. Also one of the resonant cavity holes is fitted with an output coupling loop 11, the lead 12 to which passes along a radial slot extending from the said cavity hole to the exterior of the block and enters into a glass-to-metal thimble sidearm 13 closing the slot, the end 14 of the lead being sealed through the glass thimble closure 15 of the sidearm in known manner.

Alternate anode segments between the resonant cavities are strapped together on each side of the anode partition 3 by wire coupling straps 16 in a known system of strapping utilising two straps on one side of the block, as shown in Figure 2, and four straps on the other side of the block, as indicated in Figure 2a, in which only the details required to indicate the strapping have been shown. The ends of the metal block are closed by circular copper end plates 17 attached to the block by gold washer seals in known manner (one of the plates being omitted in Figures 1 and 2), and metal cooling fins are soldered to the exterior of the block in the completed device; these fins have been omitted from the drawings in order not to obscure the other details of structure.

The construction so far described does not differ from a known construction for a magnetron oscillator device adapted to operate at a wavelength of say, 10 cms. In accordance with the invention, however, one of the resonant cavities is provided with an auxiliary thermionic cathode, and for convenience this cavity is chosen as the next-but-one to that containing the coupling loop. A cylindrical indirectly heated auxiliary thermionic cathode 18, also provided with end discs 19, is supported coaxially within the circular hole part of the said cavity by two stout conductors 20 lying one on either side of the central anode partition 3 and insulatingly sealed through the adjacent curved wall of the block through glass-to-metal thimble sidearm seals 21 similar to, and lying at right angles to, the sidearm seals 10 for the main cathode, the conductors 20 providing the cathode and heater leads for the auxiliary cathode in the same way as the conductors 9 provide the cathode and heater leads for the main cathode.

The auxiliary thermionic cathode consists of a hollow tube 22 within which lies the heater 23, the outer surface of the tube being coated with electron emissive material (not indicated) in the usual way, and the tube is cut by a narrow slot 24 (see Figure 1) extending the whole length of the cathode tube parallel to its axis. The tube 22 is insulated from one end disc 19 for enabling current to be passed through the heater 23 from the conductor 20.

In one form of this construction, designed for normal operation at a wavelength of about 10 centimetres, the magnetron block had the following dimensions:

Mms.

(a) Diameter of electron orbit space.....	16
(b) Axial length of electron orbit space.....	20
(c) Diameter of main cathode.....	6
(d) Radial depth of the parallel-sided slot part of the resonant cavities.....	3.3
(e) Width of said slot part (d).....	2.2
(f) Diameter of the circular hole part of said resonant cavities.....	10
(g) Diameter of auxiliary cathode.....	5

When this magnetron oscillator device was pulse operated in a magnetic field of 1735 oersted, the anode to main cathode voltage being 17,000 volts, the anode current being 25 amps, the pulse repetition rate being 500 per second and the pulse duration being 1 microsecond, it was found that with the auxiliary cathode not energised and left "floating," the nominal output frequency was obtained and the efficiency was about 63%. When the auxiliary cathode was connected directly to the anode the output frequency decreased by about 2 mc./s. and the efficiency fell by about 5%.

When the frequency shift was increased to 5 mc./s. by increasing the diode current by applying a biasing voltage between its anode and cathode, the efficiency fell by about a further 11%.

This use of the magnetron oscillator device is illustrated schematically in Figure 4 of the accompanying drawings, in which the device is represented only by the anode block 1, and in which for simplicity the heating circuits for the main and auxiliary cathodes, and the means for applying the magnetic field, have all been omitted.

The main operating circuit for the magnetron device is represented by the modulator M connected between the anode 1 and cathode 7 for the application of negative voltage pulses to the cathode 7, and by the waveguide load W connected to the output coupling loop 11. The auxiliary thermionic cathode 18 is connected to the anode through a switch S, and a source of bias voltage B, which is omitted if a simple switching action only is required.

Alternative ways of energising the auxiliary diode are illustrated in Figures 5 and 6, in which parts corresponding to those in Figure 4 are indicated by the same reference numerals as in that figure.

In the arrangement of Figure 5, the auxiliary thermionic cathode 18 is connected to the negative terminal of the modulator M through the switch S and a resistor R, which may be for example of about 14,500 ohms resistance for a magnetron device having the dimensions and operating conditions quoted.

In the arrangement of Figure 6, the auxiliary cathode 18 is connected through the switch S to the junction of a resistor (T₁T₂) connected between the output terminals of the modulator M; for a magnetron device having the dimensions and operating conditions quoted, the values of T₁ and T₂ may be, for example, respectively 6950 ohms and 6000 ohms.

In some circuit arrangements it may be desirable to maintain the auxiliary magnetron diode introduced in accordance with the invention permanently operative. Thus with a magnetron device in accordance with the invention as shown in Figures 1 to 3, if the oscillator anode current is varied, it is found that over a wide range of at least the higher values of oscillator anode current the frequency shift resulting from the presence of the diode decreases as the anode current increases. In pulsed operation this effect may be obtained with either of the arrangements shown in Figures 5 and 6 by shorting out the switch 5 and varying the modulator output voltage, the frequency shifts, and the changes in the frequency shifts, being different in the two cases.

Such variations of the frequency shift can be arranged to reduce to a considerable extent the "frequency pushing" experienced with magnetron oscillator devices of the type specified in operation, that is to say the change in operating frequency which occurs when the oscillator anode current is varied from a given value, as is sometimes required. Thus if the operating frequency of a magnetron oscillator device of the type specified not provided with an auxiliary cathode in accordance with the invention is plotted against the oscillator anode current, it is found that the curve exhibits a maximum, the frequency decreasing with variation of the anode current

in either direction from a particular value of anode current. But when provided with an auxiliary cathode forming a magnetron diode connected as shown in Figure 5 or Figure 6 with the switch 5 shorted out and the resistor R, or resistors T₁ and T₂, of suitable resistance, it can be arranged that for values of the oscillator anode current above the said particular value, the change in the frequency shift with change in the oscillator anode current compensates for the "frequency pushing" effect to a large extent.

For operation of the magnetron oscillator device in accordance with the invention below the said particular value of oscillator anode current, a biasing control of the diode anode-cathode voltage is required to ensure that the diode current decreases as the oscillator anode current increases; in pulse operation this may be effected by applying a reversed polarity pulse to the diode simultaneously with, but of duration greater than, the oscillator pulse.

I claim:

1. A multiple resonant cavity magnetron oscillator device comprising a metal block anode having a cylindrical electron orbit hole, a main magnetron cathode within said orbit hole, said block having a plurality of resonant cavities recessed therein, the cavities being spaced around the main magnetron cathode and opening on to the electron orbit hole, a single auxiliary thermionic cathode, said cathode being disposed within one only of the said resonant cavities, and leads to the auxiliary thermionic cathode for energizing and supplying operating current to the auxiliary magnetron diode formed by the cooperation of the said anode and said auxiliary cathode, said auxiliary cathode being slotted along its length for reducing the induction of circulating currents therein in the operation of the device.

2. A magnetron oscillator device according to claim 1 wherein the resonant cavities are formed by cylindrical slots traversing the metal block anode with their axes parallel to the electron orbit hole, and the auxiliary thermionic cathode is also cylindrical and arranged with its axis parallel to the axis of the electron orbit hole.

3. A magnetron oscillator device according to claim 2 wherein the auxiliary cathode is of substantially circular cross-section and is arranged coaxially within a part of a resonant cavity which part is of substantially circular cross-section.

4. An electric circuit arrangement comprising a mag-

netron oscillator device in accordance with claim 1 in combination with means for energising the main magnetron oscillator, and means for energising the auxiliary magnetron diode at below the cut-off voltage for the diode, the last said means including switch means for alternatively making and breaking the auxiliary magnetron diode anode-cathode circuit for varying the operating frequency of the magnetron oscillator.

5. An electric circuit arrangement according to claim 10 4 comprising a pulse modulator connected between the anode and cathode of the magnetron oscillator device for the application of high voltage operating pulses thereto, and wherein the said auxiliary thermionic cathode is connected to the output of the pulse modulator through the said switch means and through a resistance, for the application of the voltage pulses with reduced amplitude between the anode and cathode of the auxiliary magnetron diode when said switch means is closed.

6. A magnetron oscillator device according to claim 20 1 wherein the auxiliary thermionic cathode is slotted parallel to its longitudinal axis along the whole of its length.

7. A multiple resonant cavity magnetron oscillator device comprising a metal block anode having a circular cylindrical electron orbit hole, a main magnetron cathode in said orbit hole, said anode having a plurality of resonant cavities recessed into the block, the cavities being spaced around the main cathode and each consisting of a circular cylindrical slot whose axis is parallel to the axis of the electron orbit hole and a radial slot narrower than the diameter of the cylindrical slot connecting the latter to the electron orbit hole, a single auxiliary thermionic cathode located wholly within a circular cylindrical slot part of only one resonant cavity, and leads to the auxiliary thermionic cathode for energizing and supplying operating current to the auxiliary magnetron diode formed by the cooperation of said anode and said auxiliary cathode.

8. A magnetron oscillator device according to claim 7 wherein the auxiliary thermionic cathode is circularly cylindrical and coaxial with the circular cylindrical slot 40 part of the resonant cavity in which it is located.
